UNITED STATES PATENT OFFICE.

JOHN M. LANGFORD, OF LEESVILLE, SOUTH CAROLINA.

RAIL-JOINT.

1,145,321.

Specification of Letters Patent.

Patented July 6, 1915.

Application filed November 6, 1914. Serial No. 870,671.

To all whom it may concern:

Be it known that I, JOHN M. LANGFORD, a citizen of the United States, residing at Leesville, in the county of Lexington and 5 State of South Carolina, have invented new and useful Improvements in Rail-Joints, of which the following is a specification.

This invention relates to improvements in means for connecting and supporting the 10 meeting ends of two railway rails.

To this end the invention has primarily in view a novel and practical construction of angle bars which include depending side members in the form of a saddle or yoke, a 15 member being wedged between the yokes and the meeting ends of the rails so that the joint is effectively reinforced and danger of sinking of the rail ends greatly reduced if not entirely overcome.

20 It is also my purpose to provide simple but novel means for retaining the wedge member against longitudinal movement with relation to the saddles or yokes, to prevent the outward spreading of the said saddles 25 or yokes and also to adjust the height of the said member so that the same will firmly engage with the rails, locking keys being provided for the adjusting means which contact with the longitudinal edges of the 30 rails so that the block or wedge member is held both at its top and bottom against movement.

With these and other objects in view, which will more readily appear as the nature 35 of the invention is better understood, the same consists in the novel construction, combination and arrangement of parts hereinafter more fully described, illustrated and claimed.

40 The essential feature of the invention involved in the provision of my rail joint is necessarily susceptible of a range of structural modifications without departing from the scope of the invention, but a desirable 45 illustrative embodiment of the same is illustrated in the accompanying drawing, in which:

Figure 1 is a side elevation of two rails connected in accordance with the present invention, Fig. 2 is a bottom plan view of the 50 same, Fig. 3 is a vertical transverse section on the line 3—3 of Fig. 1, Fig. 4 is a perspective view of the truss or wedge block,

looking toward the bottom thereof, and Fig. 5 is a perspective view of one of the angle 55 bars.

Referring now to the accompanying drawing, in which similar reference characters represent similar parts throughout, R—R indicate two rails of the ordinary construc- 60

tion and which have their ends meeting. The webs of the rails are provided with the usual bolt openings which register with similar openings in the vertical plates of similar angle bars 1 which are arranged upon 65 the opposite sides of the rail ends. The usual bolts and nuts are provided for securing the angle bars to the rails.

The horizontal plate of each of the angle bars is integrally formed with a depending 70 saddle or yoke 2, the side arms of which being angular, or extending upwardly at opposite angles from the connecting member 3.

The saddles or yokes are of an equal thickness throughout and are preferably rectangular in cross section, while the lower edges of the said yokes are centrally formed with inwardly extending lugs 4.

The numeral 5 designates a wedge or brace block for the trusses provided by the saddles or yokes. This block upon its under- 80 face, and at a suitable distance from its opposite sides is provided or formed with a substantially rectangular depression or pocket 6, while the said sides beyond the 85 outer walls of the pocket are slotted longitudinally to provide lips 7. The lips 7 are adapted to receive the upper edges of the connecting member 3 of the saddles or yokes, while the depression or pocket 6 receives 90 the lugs 4 provided centrally upon the lower edges of the said connecting members of the saddles or yokes. It should here be stated that the lower portion of the wedge or brace block 5 is of a width equaling the length of 95 the connecting members 3 between the side arms of the saddles or yokes, and by an arrangement as just described it will be seen that the interengagement between the block 5 and the connecting members of the yokes 100 prevents either an outward or inward movement or spreading of the yokes and likewise secures the block upon the said yokes.

The adjusting or wedging feature of the block 5 is in the nature of two wedge plates 105 8—8, both being of a similar construction.

The wedge plates each comprises a member of a width or length greater than the width of the base flanges of the rails, and therefore of a greater length than that of the 5 horizontally straight top of the block 5. Each of the members 8 has one of its faces beveled from one of its ends toward its opposite end, and each of the said members is provided with a plurality of perforations, 10 two of such perforations in each of the blocks or wedge members 8 alining when the members move longitudinally one over the other between the upper face of the block 5 and the underfaces of the base flanges of 15 the rails at the meeting ends thereof, and these registering or alining openings are arranged in a line with the outer longitudinal edges of the base flanges of the rails as well as with the longitudinal edges of the horizontal members of the angle bars between 20 the side arms of the saddles or yokes. Securing elements, preferably in the nature of cotter pins, indicated by the numerals 9, are passed through the said openings, the same 25 contacting with the longitudinal edges of the base flanges of the rail and not only serve to adjust the block and lock the same upon the saddles or yokes but also serve as means for assisting in preventing the twisting or lateral movement of the rails at the 30 meeting ends thereof.

Other embodiments will suggest themselves to those skilled in the art, and it is believed that the device as described will

exemplify the uses and advantages of the 35 improvement claimed.

Having thus described the invention, what I claim is:

1. A rail joint including angle bars, connected with the rails, yokes depending from the angle bars, the connecting members of the yokes having inturned lugs, a block having its sides formed with lips and its bottom provided with a pocket, said block adapted to be arranged between the yokes and to 40 have its lips receive the connecting members of the yokes and the lugs of the yokes received within the pocket of the block, and wedge plates between the top of the block and the meeting ends of the rails. 50

2. A rail joint including angle bars which are connected to the rails, yokes depending from the angle bars, a block arranged between the yokes and removably connected therewith, wedge plates between the top of 55 the block and the meeting ends of the rail, connecting members for the wedge plates, and said connecting members adapted to contact with the angle bars between the side arms of the yokes and with the longitudinal 60 edges of the rails at the meeting ends thereof.

In testimony whereof I affix my signature in presence of two witnesses.

JOHN M. LANGFORD.
